EPHRAIM THOMAS, OF MIDDLEBORO, MASSACHUSETTS.

Letters Patent No. 62,980, dated March 19, 1867.

IMPROVEMENT IN HORSE-SHOE NAIL MACHINES.

The Schedule referred to in these Letters Patent and making part of the same.

TO ALL PERSONS TO WHOM THESE PRESENTS SHALL COME:

Be it known that I, EPHRAIM THOMAS, of Middleboro, in the county of Plymouth, and State of Massachusetts, have invented a new and useful machine for making Horse-Shoe Nails, and do hereby declare the same to be fully described in the following specification, and represented in the accompanying drawings, of which—

Figure 1 is a top view.

Figure 2, a front elevation; and

Figure 3, a longitudinal section of it.

Figure 4 is a transverse section taken through the header.

Figure 5 is a top view.

Figure 6, a side view; and

Figure 7, an inner end view of the bed-knife.

Figure 8, a top view.

Figure 9, an inner edge view; and

Figures 10 and 11 are side views of the stationary dies.

Figure 12 is an under side view; and

Figure 13 is a transverse section of the nail-plate as formed for being cut in the machine, that is, such plate has a head-rib, *a*, extended from it at one edge of it, the other edge being tapered to a wedge-shape, as shown at *c*.

The machine, in many respects, resembles a cut-nail machine, that is, such a machine as is ordinarily used for making what are termed "cut nails." The frame of the machine is exhibited at *A*, it being provided with a cam-shaft, *B*, in which are fixed two cams, *b c*, a crank-wheel, *d*, and a balance-wheel, *e*. *C* is the bed-knife, which is formed with a channel, *s*, for receiving and guiding the head projection *a*, while the nail-plate is in the act of being fed into the machine. A cutter, *D*, operates with the said knife in separating each nail blank from the nail-plate, such cutter being fixed in a rocker-shaft or frame, *E*, to which a reciprocating motion is imparted by means of an arm, *f*, extended from it, and jointed to one end of a connecting-rod, *g*, whose other end is applied to the crank-pin of the crank-wheel *d*. The header shown at *H* projects from a rocker-frame, *F*, which, at the proper periods, is raised upward by means of a pitman, *G*, which rests on an ear, *h*, projecting from the rocker-frame *E*. The machinery for supporting and operating the movable cutter and the header is essentially like such as is in use in the common cut-nail machines, and therefore needs no further description. Below the bed-knife *C* are three stationary dies, *K*, *M*, *N*. In advance of the die *K* is a movable gripping die, *L*, which operates with the die *K*, the two being formed so as to make what are termed the back slopes of the head of the nail, this being shown at *i i*, in Figure 14, which is a side view of the nail as it appears after its formation by the machine. The point is made by cutting one edge of the nail; viz, as shown at *k l*, in fig. 14, a portion, *k l m*, represented by dotted lines, being removed from the nail in order to make the point. The point is to be properly finished by the farrier during the process of straightening the nail and preparing it for being driven into the hoof of a horse. The portion so separated from the nail is cut off by the front shear *O*, and the stationary die *N*. This front shear and the gripping die *L* are fastened to projections *Q R*, from a horizontal shaft *S*, from which an arm, *T*, extends and bears against the cam *e*. There is a spring, *U*, for retracting the arm *T*. There is a spring-gauge, *V*, and a nipper, *W*, to the machine, they being like what are used in common cut-nail machines, and while in operation perform the same functions in this machine as they do in others, that is, the gauge stops the nail-plate when fed into the machine, and guides the blank down after being cut from the plate. The nipper holds the blank, and, with the die *M*, turns it ninety degrees preparatory to its being caught by the gripping dies.

In the operation of this machine, the nail-plate is to be fed along into it with an intermittent motion, and up to the gauge *V*, after which the movable cutter, *D*, descends and separates a blank from the nail-plate and forces such blank downward. Next, the nipper comes into operation with the die *M*, turns or revolves the blank ninety degrees, so as to enable the gripping dies to seize it in a proper manner. The movable gripping die next comes up and holds the blank firmly against the stationary gripping die. Next, the header advances and upsets the head and causes the gripping dies to form the back slopes of the head, which they will do by the

metal being pressed and expanded into them. During the advance of the movable gripping die the front shear O is moved up toward its fellow die or shear, N, the two operating to remove from the blank the surplus metal necessary to be removed therefrom in making the point. Next, the nail drops from the machine.

I claim the bed-knife as made with the channel s, for receiving and guiding the head projection of the nail-plate during its entrance into the machine.

I also claim the combination of the point shear O, and its fellow shear N, with the dies for separating the blank from the nail-plate, and heading it as described.

EPHRAIM THOMAS.
